Fraudges and Richard
ATTORNEYS—

UNITED STATES PATENT OFFICE.

SAMUEL M. RIKER, OF CHESTER, NEW JERSEY.

CROCHET NEEDLE.

1,409,581.

Specification of Letters Patent. Patented Mar. 14, 1922.

Application filed December 29, 1920. Serial No. 433,819.

To all whom it may concern:

Be it known that I, SAMUEL M. RIKER, a citizen of the United States, residing at Chester, in the county of Morris and State of New Jersey, have invented certain new and useful Improvements in Crochet Needles; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in needles; and, the present invention has reference, more particularly, to a novel construction of crochet-needle, comprising in combination with the shank or stem of the needle, a finger-receiving element or guard, said shank being formed between its ends with a thinned and flattened-out portion, upon which is detachably mounted a clamping element provided with said finger-receiving member for operatively arranging the needle upon the forefinger of a person.

The present invention has for its principal objects to provide a needle for crocheting or other analogous uses, which is of a simple and inexpensive construction, and the shank of which is provided with a detachably mounted finger-receiving element or guard, providing an efficient means for properly arranging the needle for use upon the forefinger of the operator, in such a manner that the needle is effectively held in place, and prevents the usual cramping or tiring effect caused by holding the straight needle of the usual and common construction between the thumb and forefinger, while with the finger-receiving element or loop of the present construction, the needle, while crocheting, is properly held against the forefinger of the operator without any contact or pressure of the thumb against the shank of the needle, as heretofore, and thus by the free movement of the forefinger permitting of a free and of a wide scope of movement of the working point or tip of the needle.

Other objects of the present invention not at this time more particularly enumerated will be clearly understood from the following detailed description of the present invention.

With the various objects of the present invention in view, the said invention consists,

primarily, in the novel crochet-needle herein-after more fully set forth; and, the invention consists, furthermore, in the novel arrangements and combinations of the various devices and parts, as well as in the details of the construction of the said parts, all of which will be more fully described in the following specification, and then finally embodied in the clauses of the claim which are appended to and which form an essential part of the said specification.

The invention is clearly illustrated in the accompanying drawings, in which:

Figure 1 is a perspective view of a crochet-needle made according to and embodying the principles of the present invention, said view illustrating in connection with the hand of the operator, the application of the crochet-needle, by means of the finger-receiving element or guard, to the forefinger of the hand.

Figure 2 is a top or plan view of the needle and the said finger-receiving element or guard; Figure 3 is a bottom view of the same; and Figure 4 is a transverse vertical section of the said needle and finger-receiving element, said section being taken on line 4—4 in said Figure 2.

Similar characters of reference are employed in all of the said above described views, to indicate corresponding parts.

Referring now to the several figures of the drawings, the reference-character 1 indicates the shank or main stem of the usual and general construction of crochet-needle, usually made from a continuous piece of tempered wire, which is formed at its one end-portion with a work-point or crocheting tip 2, and at a suitable point intermediate said point or tip and the end-portion 3, with the oppositely disposed and suitably shaped flat surface-portions 4. Upon the thinned part of the shank or stem, thus provided by said flat surface-portions, is detachably mounted a finger-receiving element or loop of the general configuration and construction to be presently described.

The said finger-receiving element or loop consists, essentially, of a wing-carrying plate or base 5 formed at its opposite edges with thin resilient wings, as 6 and 7, said wings being suitably curved in opposite directions and then extending upwardly and terminating toward each other, as at 8. Extending from one of said wings, as 6, in a direction toward the working-point or tip 2 of the needle, is an extension 9 which is

formed with a laterally extending and upwardly curved portion 10, said portion 10 being curved or bent in a downward direction, as at 11, and terminating in an inward direction in the form of a retaining finger or tongue 12, beneath the upwardly curved portion 10, and all arranged and constructed so as to preferably provide a flattened-out or oval-shaped tubular holding or clamping member, as will be clearly evident.

Extending from the other wing 7, in a direction toward the end-portion 3 of the shank or stem, is an extension 13 which is formed with a laterally extending and upwardly curved portion 14, said portion 14 being curved or bent in a downward direction, so as to provide a marginal flange 15, substantially as shown in Figure 3 of the drawings.

As shown, spaces 16 and 17 are thus provided between the opposite end-edges of the wing-carrying plate or base 5 and the respective clamping or retaining members hereinabove described. From an inspection of Figures 1, 2 and 3 of the drawings, it will readily be seen, that the shank or stem of the needle can easily be inserted in a positively clamped or held relation with said main plate or base 5, and with the said tubular holding or clamping member, formed by the parts 10, 11 and 12, and with the curved portion 14 and its marginal flange 15, in the manner illustrated more particularly in said Figures 2 and 3, the various parts being securely held in their detachably assembled relation by the frictional contact of the side-portions of the shank or stem with the alternately disposed surface-40 portions of the main plate or base 5 and the inner surface-portions of the tubular holding or clamping member, located at one end of said plate or base 5, and with the inner surface-portions of the curved portion 14 and marginal flange 15, located at the other end of said plate or base 5.

Any further description of the device is deemed unnecessary, except to state that the general arrangements and constructions of the assembled devices are most simple and efficient, the finger-receiving element or guard being readily attached and secured in its mounted position upon the shank or stem of the usual construction of crochet-needle, whereby the needle may be readily and conveniently used without cramping the hand or forefinger and thumb of the user, as is so common with needles of the usual and common straight shanks or stems, which necessitates the needle being held with more or less force between the thumb and forefinger.

While in the foregoing I have described the present invention as applied to the shank or stem of a crochet-needle, it will be understood that the principles of the in-

vention may be applied to shanks or stems of the various kinds, adapted for use to numerous purposes other than crochet-work.

I am also aware, that changes may be made in the general arrangements and combinations of the various devices and parts, as well as in the details of the construction of the said parts, without departing from the scope of the present invention as set forth in the foregoing specification, and as defined in the clauses of the claim which are appended to the said specification. Hence, I do not limit my present invention to the exact arrangements and combinations of the devices and parts, as described in the said specification, nor do I limit myself to the exact details of the construction of the said parts, as illustrated in the accompanying drawings.

I claim:—

1. In combination with a shank or stem adapted for use as a crochet-needle, or the like, said shank being provided with flat surface-portions, a finger-receiving element detachably mounted upon said flat surface-90 portions of the shank or stem, to prevent turning of the finger-receiving element upon said shank.

2. In combination with a shank or stem adapted for use as a crochet-needle, or the like, said shank being provided with flat surface-portions, a finger-receiving element detachably mounted upon said flat surface-100 portions of the shank or stem, to prevent turning of said finger-receiving element upon said shank, said finger-receiving element comprising a wing-carrying plate or base, and shank or stem-engaging means located at the opposite ends of said plate or base.

3. In combination with a shank or stem adapted for use as a crochet-needle, or the like, said shank being provided with flat surface-portions, a finger-receiving element detachably mounted upon said flat surface-110 portions of the shank or stem, said finger-receiving element comprising a wing-carrying plate or base, a tubular shank or stem-engaging member at one end of said plate or base, and a receiving member at the other end of said body provided with a marginal guide-flange, all arranged for receiving said shank or stem for mounting said finger-receiving element upon said shank or stem, to prevent turning of the finger-receiving element upon said shank.

4. In combination with a shank or stem adapted for use as a crochet-needle, or the like, said shank being provided with flat surface-portions, a finger-receiving element adapted to be detachably mounted upon said flat surface-portions of the shank or stem, to prevent turning of said finger-receiving element upon said shank, said finger-receiving element comprising a base or plate, and a 130

- pair of resilient wings extending from the opposite edges of said base, said wings being curved in opposite directions and terminating toward each other.
- 5 5. In combination with a shank or stem adapted for use as a crochet-needle, or the like, said shank being provided with flat surface-portions, a finger-receiving element adapted to be detachably mounted upon said
- 10 flat surface-portions of the shank or stem, to prevent turning of said finger-receiving element upon said shank, said finger-receiving element comprising a base or plate, a pair of resilient wings extending from the opposite
- 15 edges of said base, said wings being curved in opposite directions and terminating toward each other, a shank or stem-engaging means connected with and extending from said wings.
- 20 6. In combination with a shank or stem adapted for use as a crochet-needle, or the like, said shank being provided with flat surface-portions, a finger-receiving element adapted to be detachably mounted upon said
- flat surface-portions of the shank or stem, 25 said finger-receiving element comprising a base or plate, a pair of resilient wings extending from the opposite edges of said base, said wings being curved in opposite directions and terminating toward each other, a 30 tubular shank or stem-engaging means connected with and extending from an edge of one of said wings, a receiving member connected with and extending from an edge of the other wing, and a marginal guide-flange 35 connected with and extending from said receiving member, all arranged for receiving said shank or stem and mounting said finger-receiving element upon said shank or stem, to prevent turning of the finger-receiving 40 element upon said shank.

In testimony, that I claim the invention set forth above I have hereunto set my hand this 23rd day of December, 1920.

SAMUEL M. RIKER.
